UNITED STATES PATENT OFFICE

ALFRED CICILIONI, OF PECKVILLE, PENNSYLVANIA

DRILLING MACHINE

Application filed September 19, 1928. Serial No. 306,900.

This invention relates to improvements in drilling apparatus and has especial reference to means for feeding a drill to its work.

An object of the present invention is the provision of a drill which is especially adapted for mining operations, which includes a jack having means whereby the drill may be adjustably positioned to properly direct the drilling operation, means being provided for readily arranging the jack structure which supports the tool operating unit of the drill so that the same may be arranged in the most advantageous position.

Another object of the invention is the provision of means mounted upon the jack for yieldingly forcing the tool to the work, and for adjusting the tool forcing means as desired.

With the above and other objects in view, the invention further includes the following novel features and details of construction, to be hereinafter more fully described, illustrated in the accompanying drawings and pointed out in the appended claim.

In the drawings:—

Figure 1 is a side view of a drill supporting jack constructed in accordance with the invention, the main post being broken away.

Figure 2 is an end view.

Figure 3 is a horizontal sectional view taken substantially on the line 3—3 of Figure 2.

Figure 4 is an enlarged section on the line 4—4 of Figure 1.

Figure 5 is a similar view on the line 5—5 of Figure 2.

Referring to the drawings in detail wherein like characters of reference denote corresponding parts, the reference character 10 indicates the main post of the jack which may be of tubular construction. A threaded extension 12 on the lower end of the post is provided with a pointed foot 13 to engage the floor, so that the post may be supported between the floor and ceiling and adjusted to the desired height. The extension 12 is provided with an opening for the reception of a bar 14 to facilitate adjustment.

Mounted upon the post 10 is a horizontally disposed radially arranged arm 15 and the

inner end of this arm carries a clamp 16 by means of which the arm is secured to the post. The clamp 16 is rotatable and slidable upon the post and in order to hold it against accidental movement, a screw 17 extends through the clamp and engages within any one of a number of spaced openings 18 provided in the post. The vertical or horizontal position of the radial arm 15 may thus be regulated.

Slidably mounted upon the arm 15 is a carrier block 19. This block may be adjusted longitudinally of the arm 15 and held in adjusted position by clamping nuts 20. Carried by the block 19 is a guide arm 21 and slidably mounted upon this arm is a carriage 22 which supports a tool operating unit 23. This unit carries a drill 24 whose shank is movable in a guide 25 at the outer end of the arm 21. A suitable operating agent may be fed to the drill unit 23 through a pipe 26 which is controlled by a valve 27.

The inner end of the arm 21 supports a block 28 and pivotally mounted upon this block as shown at 29 is the inner end of an actuating or pusher arm 30. The outer curved end 30' of this arm has pivotal connection 31 with the outer end of a rod 32, and the inner end of this rod is pivotally connected as at 33 to the carriage 22. This carriage is freely slidable along the arm 21 and for this purpose is provided with anti-friction rollers 33a. The actuating arm 30 is adapted to yieldingly force the carriage outward so as to fit the drill to its work, and for this purpose there is provided a spring 34 which is positioned upon one side of the arm 21. The inner end of this spring is secured to an arm 28' as shown at 35. This arm 28' is fixedly secured to the block 28. Any suitable means may be provided for securing the spring to the arm 28', such as a pin removably engaged in any one of a number of spaced openings 36 provided in the arm. The position of the inner end of the spring may thus be adjusted with respect to the pivot pin 29 of the arm 30 in accordance with the particular character of the work.

A turnbuckle 37 is arranged between the spring and arm 28', while the end of the

spring is secured to the curved end of the arm 30 as shown at 38.

- It will be apparent from the foregoing description and accompanying drawings that
- 5 when the drill is in use the action of the spring 34 will be to force the carriage outward, so that the drill will be automatically fed to the work as the drill operation progresses.
  - 10 If desired, a weight 40 may be provided to assist the spring 34 in its work. This weight is secured at the outer end of a cable 41 and the latter is turned over horizontally spaced pulleys 42 which are supported at the upper
  - 15 end of the post 10. The cable also passes around a pulley 43 spaced downward from the pulleys 42 and supported by the post 10 and has its other end attached to the pivot 31 which connects the arm 30 and the rod 32.
  - 20 The invention is susceptible of various changes in its form, proportions and minor details of construction and the right is herein reserved to make such changes as properly fall within the scope of the appended
  - 25 claim.

Having described the invention what is claimed is:

- In a device of the character described, a guide arm, means to support said arm, a carriage movable along the guide arm, a tool operating unit secured to the carriage, a tool extending from the said unit, a pusher arm pivotally mounted upon the inner end of the guide arm, a rod having one end pivotally
- 30 secured to the inner end of the pusher arm, means to secure the other end of the rod to the carriage, whereby relative movement of the pusher arm and rod will move the carriage longitudinally of the guide arm, and
  - 35
  - 40 a spring having one end anchored fixedly with respect to the guide arm and its other end secured to the pusher arm to yieldingly force the carriage outward.

In testimony whereof I affix my signature.

ALFRED CICILIONI.
